CLAIM

The ornamental design for a folding multipurpose hand tool, as shown and described.

DESCRIPTION

FIG. 1 is a perspective view of a folding multipurpose hand tool according to our new design, shown with pliers in an open position;

FIG. 2 is a right side elevation view thereof;

FIG. 3 is a front elevation view thereof;

FIG. 4 is a top plan view thereof;

FIG. 5 is a rear elevation view thereof;

FIG. 6 is a left side elevation view thereof;

FIG. 7 is a bottom plan view thereof;

FIG. 8 is a perspective view of the folding multipurpose hand tool, shown in a closed position;

FIG. 9 is a rear elevation view thereof;

FIG. 10 is a right side elevation view thereof;

FIG. 11 is a front elevation view thereof;

FIG. 12 is a top plan view thereof;

FIG. 13 is a bottom plan view thereof;

FIG. 14 is a left side elevation view thereof; and,

FIG. 15 is a front elevation view thereof, shown with a knife blade in an operable position.

The broken lines shown herein are for illustrative purposes only and form no part of the claimed design.
